UNITED STATES PATENT OFFICE

165,829

SWIVEL TABLE

Robert Dorr, Jr., Beverly Hills, Calif., assignor, by
mesne assignments, to International Furniture
Company, a corporation of Illinois

Application May 19, 1948, Serial No. 146,468

Term of patent 14 years

(Cl. D33—14)

To all whom it may concern:

Be it known that I, Robert Dorr, Jr., a citizen of the United States, residing at Beverly Hills, county of Los Angeles, and State of California, have invented a new, original, and ornamental Design for a Swivel Table, of which the following is a specification, reference being had to the accompanying drawing, forming a part thereof, in which:

Figure 1 is a perspective view of a swivel table showing my new design; Fig. 2, a top plan view; Fig. 3, a side view in elevation; and Fig. 4, a sectional view, the section being taken as indicated at line 4—4 of Fig. 3.

I claim:

The ornamental design for a swivel table, as shown.

ROBERT DORR, JR.
